UNITED STATES PATENT OFFICE.

JOSEF ČERNÝ, OF LEOMINSTER, MASSACHUSETTS.

DESIGN FOR A COMBINATION PENHOLDER AND SAFETY COLLAR.

Application filed March 27, 1923. Serial No. 5,612. Term of patent 3½ years.

To all whom it may concern:

Be it known that I, JOSEF ČERNÝ, a citizen of Czechoslovakia, residing at Leominster, in the county of Worcester and State of Massachusetts, have invented a new, original, and ornamental Design for Combination Penholder and Safety Collar, of which the following is a specification, reference being had to the accompanying drawing, forming a part thereof.

In the drawing, Fig. 1 is an upper perspective view of my combination pen holder and safety collar; Fig. 2 is a lower perspective view of the same; showing my design.

I claim:

The ornamental design for a combination penholder and safety collar, as shown.

In witness whereof I have affixed my signature.

JOSEF ČERNÝ.
